TELL-TALE FLEXIBLE STAYBOLT

Application filed January 20, 1931. Serial No. 509,996.

This invention relates to staybolts for boilers, and has special reference to staybolts of flexible type.

Under the Interstate Commerce Commission rules it is required that all flexible staybolts having caps over the outer ends shall have the caps removed at least once every two (2) years and the bolts and sleeves examined for breakage, except in cases where the bolt is provided with a tell-tale hole not less than three-sixteenths ($\frac{3}{16}$) of an inch nor more than seven thirty-seconds ($\frac{7}{32}$) of an inch in diameter, extending the entire length of the bolt and into the head not less than one-third ($\frac{1}{3}$) of its diameter, and these holes are protected from being closed by copper plating or other approved method, and are opened and tested, each time (at least yearly) the hydrostatic test is applied, with an electrical or other instrument approved by the bureau of locomotive inspection, that will positively indicate when the tell-tale holes are open their entire length, in which cases the caps will not be required to be removed. When this electrical indicating test is completed the hydrostatic test must be applied and all staybolts removed which show leakage through the tell-tale hole.

The Interstate Commerce Commission rules further require that the inner ends of the tell-tale holes must be kept closed with a fire-proof porous material that will exclude foreign matter and permit leakage of steam or water, if the bolt is broken or fractured, into the tell-tale hole, and that when this test is completed the ends of the tell-tale holes must be closed with material of different color from that removed and a record kept of colors used.

In order to avoid the troublesome, tedious and time-consuming work of removing the caps of the large number of staybolts on a locomotive and the necessity of stripping the entire fire-box of the jacket, lagging, piping, etc., and the withdrawal of the locomotive from service several days each time the caps must be removed and the staybolts inspected, it has been a common practice to use a special type of flexible staybolt with a cop- perized tell-tale hole complying with the re-

quirement above-noted, that is, a tell-tale hole of "blind" character extending from its inner end to a point in its head portion near its opposite or outer end, from which point outward the hole is "blind" or closed. These staybolts are difficult to make on account of drilling the small hole into the head and treatment of the tell-tale hole, and there is no assurance that the hole is drilled accurately in the center, so that faulty bolts are liable to be produced and put into use. Ordinarily this type of bolt employs a solid or screwed on spherical head fitted to turn in a casing consisting of a sleeve and cap, the cap being especially designed to close the casing against any leakage which may occur between the head and its seat due to expansion, contraction or wear of these parts or imperfections causing imperfect seating.

One objection to such construction of flexible tell-tale staybolts is that in riveting down the inner end of the bolt the tell-tale hole is liable to be closed. In such event the hole must be reamed out, cleaned by means of an air cleaner for removal of chips and other foreign particles, and all such tell-tale holes tested by means of an electrical testing tool such as before referred to which indicates by electric contact and the operation of a signal when the hole is entirely clear and clean.

Another objection to such construction of flexible tell-tale staybolts is that in case of leakage at the outer end of the bolt it is impossible to tell whether such leakage is due solely to a faulty seat or to a break in the bolt, or both, and therefore it is difficult to tell what work is necessary to remedy the difficulty.

Still another objection to such flexible tell-tale bolts is that between inspections fracture of a stay-bolt may occur which will not be indicated in the manner relied upon by leakage of water and steam through the porous closure, and the tell-tale holes of such bolts may become clogged with boiler scale so that no indication of the break can be given in the designed way. When this occurs it is necessary to clean out the tell-tale holes of all clogged bolts and to electrically test the same by means of an electrical test tool as

previously described to indicate by electric contact and the operation of a signal when the hole has been thoroughly cleaned. After all bolts have been thus tested to determine 5 whether or not their tell-tale holes are cleaned, all bolts not showing clean bolt holes must be removed. All bolts which have successfully undergone the clean tell-tale hole test must then be tested for breaks or fractures by applying water pressure to the boiler, the tell-tale holes closed by porous plugs of different color from those previously used, and elaborate records of all such tests kept; and all bolts indicating by leakage, breaks or 10 fractures into the tell-tale holes, must be removed.

As a result of the several objections above-mentioned flexible tell-tale staybolts of the type in general use are comparatively expensive to install and to maintain in serviceable 20 condition, and the difficult and tedious inspection work required encourages faulty inspection work and necessitates the withdrawal of the locomotive from service for a 25 considerable period each time general inspection and repairs are made.

The main object of our invention is to provide a staybolt so constructed as to allow of the use of a tell-tale hole of "peep-sight" 30 type, or one extending continuously therethrough, so that breaks or fractures will be at once indicated by leakage of steam or water at one end or the other end of the bolt; so that the condition of the tell-tale hole may 35 at all times be determined by visual inspection, i. e., by daylight or other light test and looking through the tell-tale hole or by means of a rod; and so that cleaning of the tell-tale hole may be performed in an easy and rapid 40 manner and without the use of complex tools.

A further object of the invention is to provide a construction of bolt head and casing and joint-closing means effecting a sealing connection therebetween, whereby an open 45 instead of a closed type of casing may be employed to permit escape of steam or water for break or fracture indication at the outer end of the bolt, as well as at the inner end thereof, while at the same time normally maintaining 50 a tight steam and water tight joint between the head and casing.

In another application, filed of even date herewith, Serial No. 509,997, we have shown the principles of our invention applied to a 55 bolt head casing arranged and welded on the outer side of the outer boiler sheet and in which casing an outer seat for the head is formed, the inner seat for the head being formed by the wall of the bolt opening in 60 such boiler sheet.

In the present application we have shown the principles of our invention applied to a staybolt having a sleeve and cap form of casing in which the sleeve is fitted in an opening 65 in an outer boiler sheet and is provided with

inner and outer seats for the head. In both applications the outer wall of the casing is provided, in accordance with our invention, with an opening exposing the tell-tale hole at the outer end of the bolt and through which the steam and water may escape for a break or fracture indicating action. It is to be understood, however, that, within the scope of the present invention, the casing may be of any suitable arrangement, construction and form, and welded to or screwed in the sheet, except as to any limitations which may be contained in the appended claims.

In the drawings:

Fig. 1 is a longitudinal section through one form of staybolt embodying our invention applied to boiler sheets.

Fig. 2 is an outer end elevation of the bolt with casing applied.

Fig. 3 is an outer end elevation of the bolt proper.

Fig. 4 is a side elevation of the bolt.

Fig. 5 is a bottom plan view of the bushing or outer bolt head section.

Fig. 6 is a sectional side elevation of the same.

Fig. 7 is a plan view of the washer.

Fig. 8 is a view similar to Fig. 6 of the gasket.

Fig. 9 is a longitudinal section showing a bolt with separately formed end extension applied thereto.

Fig. 10 is a longitudinal section showing a modified construction of casing and a modified form of bolt.

Fig. 11 is a section on the line 11—11 of Fig. 10.

Fig. 12 is a sectional side elevation of the inner bolt head or head member shown in Fig. 10.

Fig. 13 is a sectional side elevation of another modified form of casing.

Fig. 14 is a sectional view through the bolt and casing showing the use of the casing of Fig. 13 and a coiled spring and washer structure conforming to Fig. 1.

Fig. 15 is a sectional view showing another modified form of bushing or outer head member.

Fig. 16 is a longitudinal section showing the use of a coil spring instead of a plate spring in the structure of Figs. 10 and 11.

Referring now more particularly to the drawings, and especially to Figs. 1 to 8, inclusive, 1 and 2 respectively designate the inner and outer sheets of a fire-box or other portion of a boiler. In the sheet 1 is a threaded opening 3 in which is fitted and through which extends the inner threaded end 4 of the bolt 5, a projecting portion of which end 4, after the bolt is applied, is upset or hammered down to form the head 6.

The opposite or outer end of the bolt 5 is provided with a hemispherical head or head member 7, which is arranged at the point of

intersection of the main portion of the body or shank of the bolt, and a reduced end extension 8. This end extension 8 constitutes a novel and important feature of our invention, as hereinafter fully described, and may be externally of any suitable form. The head or head member 7 is given a cup-shaped formation by the provision of an annular socket or recess 9 between the same and the 10 stem or extension 8, and the rim portion of the cup-shaped head member so formed may be provided, as shown, with notches or recesses 10 to receive portions of a wrench or like tool used in rotating the bolt to thread its end 4 into the opening 3, as will be readily understood.

The outer end of the shank of the bolt and its head and coacting parts are disposed within a casing comprising a sleeve member 11 20 and a cap member 12. The sleeve member 11 is tapered at its inner end to fit within a tapered opening 13 in the sheet 2, to which the sleeve member is welded, as indicated at 14, and the outer end of the sleeve member is 25 externally threaded to receive the threaded flange of the cap member 12.

The inner end of the sleeve member is formed with a passage 15 of uniform diameter which communicates with a cup-like chamber 30 or socket 16 formed in the outer end of said sleeve member. The bottom portion of the inner wall of the socket is concaved to form a joint closing seat 17 for the convex outer surface of the head member 7 and on which said head member may turn in the flexing motions 35 of the bolt.

Slidably fitted upon the bolt stem or extension 8 is a hemispherical bushing or supplemental outer head member 18 the convex bearing face of which engages a concaved outer joint closing seat 19 formed in the bottom of the crown portion of the cap 12 and intersecting an opening 20 extending through said crown portion of the cap and through which 45 opening the bolt stem or extension 8 is exposed or projects. The seats 17 and 19 and convex bearing surfaces of the members 7 and 18 are arranged on arcs having a common center, whereby, when the parts of the bolt 50 head and its casing are properly adjusted for operation, the surfaces 17 and 19 form inner and outer parts of a bearing on which the members 7 and 18 may rotate or tilt unitarily, allowing ample freedom of flexing motion of 55 the bolt while providing coacting inner and outer joint closing surfaces to prevent the escape of steam or water between the casing and the bolt head.

The bushing or outer head member 18 is 60 provided in its underside with a cavity 20 receiving a conical gasket 21 of lead or other soft metal, whereby the joints between said parts and the stem or extension 8 are closed. This gasket 21 rests upon a washer 22 which 65 is resiliently supported by a coiled spring 23

seated in the groove 9 and surrounding the stem 8 between said washer and the bottom of the groove, the pressure of which spring, regulated by the adjustment of the cap 12, holds the gasket tightly seated against the 70 bushing and the latter against the outer seat face 19, thus providing an automatic adjustment to compensate for wear and to keep the joint constantly tight. A copper or other suitable metallic packing ring or gasket 23' 75 may be provided between the rim of the socket and crown of the cap to make a steam and water tight connection at this point.

The bolt 5 is provided with a tell-tale hole 24 extending longitudinally through it, from 80 end to end, including the extension 8. This hole, therefore, unlike the blind tell-tale hole terminating at one end in the head of the bolt, may be easily and accurately formed and furnishes a passage opening through 85 both ends of the bolt. Such a hole, if temporarily closed at its inner end in the formation of the head 6, may be easily and conveniently reamed out and cleared of all particles without the necessity of employing a 90 pneumatic cleaning tool or an electric testing device, since any sort of a cleaning instrument may be employed and whether or not the hole is clogged or open may be determined instantly by daylight or artificial light 95 visual observation, that is, by simply looking through the bolt hole. The inner end of the hole is closed in use in the prescribed manner by employing a porous plug 25, through which, in the event of breakage of 100 the bolt or fracture into the hole, steam or water may discharge at such end of the bolt to indicate the break, while the plug serves normally to prevent any of the products of combustion from the fire-box entering and 105 clogging the hole. If conditions are favorable, however, the porous plug may be omitted. In the event of leakage between the bolt head and its seats, which is not liable to occur because of the self-adjusting action 110 of the head, the nature or character of this leakage may be readily determined and distinguished from a break or fracture leak. Also in case of fracture or leakage, escape of 115 water or steam will occur from either or both ends, and at least one of the ends, of the bolt hole, thus assuring an immediate indication being given even in the event that one end of the bolt should be clogged. With a flexible bolt of ordinary construction, where the tell-tale hole is closed by a porous plug at 120 one end and is blind or terminates in the bolt head at the opposite end, it is possible, in case of a fracture, for scale to enter and clog the tell-tale hole between periods of inspection 125 without escape of steam or water, so that no indication of the fracture will be given. This is hardly possible with our improved construction, since, in the event of a break or fracture, water or steam will escape through 130

one or the other of the ends of the bolt. Assuming, however, that a fracture should occur and scale enter and clog the bolt, this condition may be determined either by sight 5 test or by the introduction of a suitable instrument, and the tell-tale hole may be quickly cleared and such condition determined and an indication of the nature of the trouble obtained, without the use of the complex 10 instrumentalities and the expenditure of the great amount of time and labor commonly required. As such construction and clearing tests may be easily and conveniently made, the tests may be conducted if desired at much 15 more frequent intervals than required by Interstate Commerce Commission rules, or is customary, and the boiler kept in better and safer condition without the expense in time and labor and withdrawal of the locomotive 20 from service as experienced with conventional staybolts in present practice. This improved construction of staybolt combines all the advantages of the rigid hollow staybolt with the tell-tale hole with the advantages 25 of the flexible type, while overcoming the stated and other well known disadvantages of the ordinary rigid and conventional types of flexible staybolts.

The construction of the staybolt may be 30 modified in many and various ways within the spirit and scope of our invention. As shown in Fig. 9 the bolt passage 15^a in the sleeve may be tapered and, in addition to the soft metal washer 21, one or more shim-like 35 additional washers 24^a may be employed. Fig. 9 also shows the use of a separately formed end extension 8^a which may be threaded and welded or otherwise fixed to the bolt shank, this construction allowing conventional stock bolts to be converted at slight 40 expense into bolts with extensions adapted for the purposes of this invention.

In Figs. 10, 11 and 12 we have shown a bolt 45 which may be inserted from the fire-box side, to which end the threaded inner end 4^a of the bolt 5^a is provided with a primarily formed head 6^a, which may be suitably constructed to permit of the application of a wrench thereto. The forward end of this bolt is 50 threaded in rear of the stem or extension 8, as at 26, to receive a separately formed internally threaded stationary or inner head member 7^a which, when applied to the bolt and adjusted for a proper seating action, may be 55 fixed in position in any desired manner. In this construction the outer face of the member 7^a is plane-surfaced and a concavo-convex plate spring 23^a is employed in place of the coiled spring 23. With these differences, 60 the construction of the bolt is the same as the bolts previously described and the functional qualifications of the bolt are also the same.

In Figs. 13 and 14 we have shown a modified form of sleeve which may be employed 65 with any of the various forms of bolts used,

in which the sleeve is provided with a tapered passage 15^b and in which the outer end 11^a of the sleeve is made with a straight thread to receive the cap and in which the outer end of the sleeve is made with a tapered thread 70 11^b to fit within a correspondingly tapered and threaded opening in the boiler sheet 2. Otherwise the structure here shown is or may be the same as that disclosed in Fig. 1.

It will, of course, be understood that the 75 gaskets and washers employed may be of metals of suitable degrees of hardness or softness, and that by making the bushing or outer head member wholly of bearing metal, the washers may be dispensed with. We may, 80 however, as shown in Fig. 15, employ a bushing or outer head member 18^a provided with a filling 21^a of lead or other soft metal, or suitable bearing metal, to serve the function 85 of a separate washer, such as washer 21, so that the number of parts may be reduced.

In the structure shown in Fig. 16 we have disclosed the use with the organization shown in Figs. 10 and 11 of a coil spring 23 instead 90 of the plate spring 23^a.

From the foregoing description, taken in connection with the accompanying drawings, the construction and mode of operation of our improved tell-tale hole flexible bolt will be 95 readily understood and its advantages appreciated by those versed in the art without a further and extended description. While the structures disclosed, for exemplification, are preferred, it will, of course, be understood that our new staybolt may be used in practically all sleeves of conventional type now 100 in use and that many changes in the form, proportion, construction, and arrangement of parts, other than those disclosed, may be made within the scope of the claims without departing from the spirit or sacrificing any 105 of the advantages of the invention.

Having thus fully described our invention, we claim:

1. In a staybolt structure, a casing comprising a sleeve and cap having outer and inner spherical seat surfaces, and said cap having an opening in its outer wall concentric with its seat surface, a bolt having an end portion disposed in said casing and provided with an inner head member having a spherical seat surface pivotally engaging the seat surface of the sleeve, an axial extension projecting beyond said inner head member and projecting outwardly through the opening in the cap, the bolt and its extension being provided with a tell-tale hole extending continuously from end to end thereof, an outer head member 115 slidable on the bolt extension toward and from the inner head member and having a spherical seat surface pivotally engaging the seat surface of the cap, and spring-pressed means acting to force the outer head member outward and away from the inner head member and against said seat surface of the cap, 120
2. In a staybolt structure, a casing comprising a sleeve and cap having outer and inner spherical seat surfaces, and said cap having an opening in its outer wall concentric with its seat surface, a bolt having an end portion disposed in said casing and provided with an inner head member having a spherical seat surface pivotally engaging the seat surface of the sleeve, an axial extension projecting beyond said inner head member and projecting outwardly through the opening in the cap, the bolt and its extension being provided with a tell-tale hole extending continuously from end to end thereof, an outer head member 125 slidable on the bolt extension toward and from the inner head member and having a spherical seat surface pivotally engaging the seat surface of the cap, and spring-pressed means acting to force the outer head member outward and away from the inner head member and against said seat surface of the cap, 130

the said outer and inner spherical seat surfaces of the sleeve and cap and coacting spherical seat surfaces of the outer and inner head members being formed on arcs described from a common center whereby the
5 sleeve and cap provide a ball and socket connection allowing universal lateral oscillation of the bolt without compression of the spring or causing separation of the joint closing members.
10 2. In a staybolt structure, a casing comprising a sleeve and cap having outer and inner spherical seat surfaces, and said cap having an opening in its outer wall concentric with its seat surface, a bolt having an end portion disposed in said casing and provided with an inner head member having a spherical seat surface pivotally engaging the seat surface of the sleeve, an integral axial extension projecting beyond said inner head member and projecting outwardly through the opening in the cap, the bolt and its integral extension being provided with a tell-tale hole extending continuously from end to end
15 thereof, an outer head member slidable on the bolt extension toward and from the inner head member and having a spherical seat surface pivotally engaging the seat surface of the cap, a packing member for closing the
20 joint between the bolt extension and outer head member, and a spring for pressing the packing against the outer head member and acting to force the outer head member outward and away from the inner head member
25 and against said seat surface of the cap, the
30 said outer and inner spherical seat surfaces of the sleeve and cap and coacting spherical seat surfaces of the outer and inner head members being formed on arcs described from a common center whereby the sleeve
35 and cap provide a ball and socket connection allowing universal lateral oscillation of the bolt without compression of the spring or causing separation of the joint closing members.
40
45 In testimony whereof we affix our signatures.
